GAME BOARD

Denis R. Alonco, Yokaham, and Naoyasu Hanayama,
Tokyo, Japan, assignors to Tradepoport, Inc., El Segundo,
Calif., a corporation of California

Filed Dec. 9, 1965, Ser. No. 133

Claims priority, application Japan Aug. 12, 1965

Term of patent 7 years

(Cl. D34—5)

FIG. 1

The dominant features of our design reside in the full line portion as shown.

We claim:

The ornamental design for a game board, substantially as shown and described.
